Des. 211,878
Patented Aug. 6, 1968

211,878

ELECTRIC FIREPLACE

Donald E. Winegardner, R.R. 8,
Huntington, Ind. 46750

Filed Aug. 7, 1967, Ser. No. 8,154

Term of patent 14 years

(Cl. D23—94)

Fig. 1.

Fig. 2.

Fig. 3.

Fig. 4.

FIG. 1 is a front elevation view of my electric fireplace, showing my new design.

FIG. 2 is a side elevation view thereof.

FIG. 3 is a top plan view thereof.

FIG. 4 is a bottom view thereof.

The dominant features of my design reside in the portions shown in full lines.

I claim:

The ornamental design for an electric fireplace, as shown and described.
